United States Patent Office.

SAMUEL DUNLAP, OF ROME, GEORGIA.

Letters Patent No. 90,999, dated June 8, 1869.

IMPROVED BED-BOTTOM.

The Schedule referred to in these Letters Patent and making part of the same.

To all whom it may concern:

Be it known that I, SAMUEL DUNLAP, of Rome, in the county of Floyd, and State of Georgia, have invented a new and useful Improvement in Spring-Beds; and I do hereby declare that the following is a full, clear, and exact description thereof, which will enable others skilled in the art to make and use the same, reference being had to the accompanying drawings forming part of this specification.

This invention relates to improvements in spring-bed bottoms, designed to provide a simple, cheap, and effective arrangement of the same.

It consists in arrangement of vulcanized India-rubber springs, upon tension-rollers at each end, extending across the space between the ends, the rollers being provided with ratchets and pawls, for tightening and holding the springs.

Figure 1 represents a plan view of my improvement;

Figure 2 represents a side elevation; and

Figure 3 represents detail views.

Similar letters of reference indicate corresponding parts.

I propose to employ India-rubber belts or straps *a*, to be extended across the space between the frame, either transversely or longitudinally, preferably in the latter direction, and secured upon rollers *e b*. I pro-

vide bearing for the said rollers in the plates *g*, of metal or other substance, so arranged as to be readily attached to or removed from the bedstead after it is put together.

Each roller is provided with a ratchet-wheel and pawl at one end, to permit the straps to be tightened by turning the rollers, and to hold them under any preferred degree of tension.

For turning the rollers, holes may be made in them for the application of a lever, or other means may be used. The journals of the rollers may be placed in the side-rails of the bedsteads, instead of the bearings *g*, if preferred.

This arrangement provides a simple and cheap spring-bed, which may be readily adjusted to any desired degree of elasticity.

Having thus described my invention,

I claim as new, and desire to secure by Letters Patent—

The combination, with a bedstead, of the India-rubber straps *a*, rollers, ratchets and pawls, and either the bearing-plates or not, all substantially as specified.

SAMUEL DUNLAP.
